UNITED STATES PATENT OFFICE.

GEORGE GLAUDEL, OF LOS ANGELES, CALIFORNIA.

SILVERING-TABLE.

1,195,351.

Specification of Letters Patent. Patented Aug. 22, 1916.

Application filed April 12, 1916. Serial No. 90,600.

To all whom it may concern:

Be it known that I, GEORGE GLAUDEL, a citizen of France, residing at Los Angeles, in the county of Los Angeles, State of California, have invented new and useful Improvements in Silvering-Tables, of which the following is a specification.

This invention relates to improvements in silvering tables and particularly in such silvering tables as set forth in my Patent No. 794,858 of July 18th, 1905.

In my Patent No. 794,858 I have described a mechanism in which there is a leveled surface and a mechanism for holding a glass plate up against that leveled surface and for then holding the plate in its leveled position when the leveled surface is removed. In such a combination as described in my said patent, my present improvement is directed particularly to the means for raising the glass plate against the previously leveled surface and for holding the glass plate in its leveled position.

It is an object of this invention to provide a simple and effective means for attaining the ends stated, and it is also an object of this invention to provide a means for accurately holding the glass plate in its leveled position without any chance of the glass plate moving out of its proper position.

I now proceed to describe as much of the complete table as is necessary to a full understanding of my present improvement and then proceed to a detailed description of the improvement itself. I refer to the accompanying drawings in which, for the purpose of this specification, I have illustrated my now preferred form of silvering table.

In these drawings Figure 1 is a vertical cross section of my improved table, Fig. 2 is a partial longitudinal section of the same; Fig. 3 is a detail plan, with parts broken away and in section taken as indicated by line 3-3 on Fig. 2, Fig. 4 is an enlarged detail section taken as indicated by line 4-4 on Fig. 1, and Fig. 5 is a partial end elevation of the table.

In the drawings the numeral 10 designates a suitable box structure having in its lower portion the heating coils 11 and having provision, as at 12, for extending a canvas or the like over the heating coils 11 to catch the water or other fluid with which the glass plate or plates 13 are washed before the silvering operation takes place.

Suitable cross beams or other supports 15 are built into the box; and on these beams I place stringers 16 as illustrated, these stringers carrying the glass raising and supporting mechanisms, as will be hereinafter described. I provide suitable glass supporting frames 17 adapted to support the glass plates 13. These frames 17 are pivoted at one edge on the shaft 18 and their other edges rest upon the suitable supporting brackets 19. I preferably place the horizontal shaft 18 centrally of the table structure and pivot the oppositely disposed frames 17, 17 to this one shaft. The means now to be described operates to raise the outer edges of the glass supporting frames to tilt the glass plate so that it may be cleansed and washed with water, the water running off onto the canvas 12. The brackets 19 are mounted upon vertical ways 80 and are moved vertically by the screws 81 mounted in bearings 82. Along each side of the table there extends a shaft 83 carrying bevel gears 84 meshing with bevel gears 85 on the lower ends of screws 81. Shafts 83 may be rotated with a crank 86; and ratchets and pawls 87 may be employed to hold the shafts 83 in any position and to thus hold the movable edges of the glass supporting frames in any position, either the position shown in the drawing or in a raised position to tilt the glass plate.

The glass plate or plates being placed on the supporting frames, the frames are easily and quickly inclined to the most advantageous position for cleansing and washing the plates. After cleansing and washing, the plates are let down to their normal position and are then ready for leveling and silvering.

I provide longitudinal ways 20 along the opposite longitudinal sides of the box or table and the leveling beams or bars 21 are supported between these ways, each beam having rollers 22 at its ends for rolling support in the ways. In their normal positions the beams 21 are all at one end of the table, the right hand end in Fig. 2. The number of these beams depends upon the length of the table and upon the distance desired between the beams when spaced apart along the table. A rope or cable 25 passes through the beams; and any suitable provision may be made for moving the cable endwise, as drums 26 at the ends of the table. This

cable is secured to the first beam 21 by any suitable means, as by collars 27; so that the first beam moves with the cable. Connective means is provided between the beams consisting of two links 28, these links having feet or lugs 29 which prevent their movement to straight line position. When the first beam is drawn out over the table the second beam follows at the distance determined by the links, and then the remaining beams follow in the same manner. When the first beam is drawn back the links collapse or fold on each other and the beams then move one against the other and all move back to the end of the table shown in Fig. 2.

On the opposite longitudinal sides of the table I place leveling plates 30; which plates 30 are initially carefully leveled; so that when the beams rest upon their upper edges they are in exactly leveled position. The ways 20 are mounted upon vertically sliding racks 31 worked by pinions 32 in the manner explained in my said patent; so that the ways may be lifted and the beams 21 may be lifted off the leveling plates 30.

In the operation of my device the glass is placed at 13 upon the frames 17 and initially cleaned or washed in the manner hereinbefore explained. The leveling beams are then run out over the glass and are lowered onto the leveling plates 30. Their lower surfaces then present an accurately leveled surface against which the glass plates may be raised. The improved mechanism for raising and holding these glass plates in position is the particular subject matter of this specification and the following claims. I have shown a plurality of raising and supporting mechanisms 50 and shall now describe one of them in detail. Each of these mechanisms embodies a suitable bearing stand 51 carrying a vertically movable plunger 52 having a glass supporting foot 49 upon its upper end. This plunger 52 is enlarged at its lower end as shown at 52^a; and around this enlarged portion I place a split ring clamp 53. This clamp is confined vertically between the two parts 51^a of the bearing stand 51. Under normal conditions this clamp will not grip the plunger 52 but will allow the plunger to move freely. The plunger is normally moved upwardly by the operation of a weight 54 mounted upon a lever 55 pivoted at 57. Weight 54 is provided with a small bearing wheel 58 adapted to ride upon a wedge 59 upon longitudinally movable bar 60. There is one of these bars for each set of the devices 50; and the bars are all moved by rack and pinion mechanism 61 at the end of the table. When a glass plate is placed on the table the bars are all moved to their positions where the wedges 59 raise the weights 54, causing the plungers 52 to be lowered, as

shown in Figs. 1 and 2. After the glass plate is in position and the leveling bars are properly placed on leveling plates 30, then the bars 60 are moved to withdraw the wedges from beneath the weights 54; with the result that the weights act to force the plungers upwardly against the glass plates and lift the glass plates against the leveling beams 21 (the beams being sufficiently heavy to prevent their being lifted). By the same act which withdraws the wedges from beneath weights 54 the clamps 53 are caused to tightly grip the plungers 52. This is accomplished by the operation of a clamp arm 70 pivoted at 71 and having a nose 72 bearing against one side of the clamp 53. The clamp 53 is made as a split ring with two projecting lugs 73; and when the clamp lever 70 is moved in the direction indicated by the arrow then the two lugs 73 are compressed together between the nose 72 and the part 51^a of the bearing stand 50. The last mentioned motion of bars 60 has been in the direction indicated by the arrow in Fig. 4. This movement compresses the spring 75, 90 the spring 75 forming the connective means between bar 60 and lever 70. The spring 75 lies around a rod 76 which is connected at 77 to the lever 70 and passes loosely through a lug 78 on the side of bar 60. 95 When the bar 60 is moved in the direction opposite to that indicated then the lever 70 is released and clamp 53 is released with the result that the plunger is free to move as has hereinbefore been explained; but when the bar 60 is moved in the direction indicated then the clamp 53 tightly grips the plunger, in whatever position the plunger happens to be, and holds it and the weight 54 immovable. The plungers having been 105 moved up to support the glass plate in position with its upper surface pressed against the accurately leveled lower surface of the beams, and the plungers having been gripped and held in their respective positions, the glass plate is now supported by the plungers in exactly leveled position. The leveling beams 21 may now be raised by raising the ways 20 and the beams removed from over the glass plates. The operation of sil- 110 vering may then be carried on efficiently as the glass plates are held in accurately horizontal position.

My improved mechanism provides for efficiently raising the glass plates against the leveling surface and for efficiently and accurately holding the plates in that position. When the plungers are raised against the glass and the glass is raised against the leveling beams, then the clamps grip and hold the plungers in precisely the position at which the plungers then stand. Upon removal of the leveling beams there is no movement whatever of the plungers; and, therefore, there is no movement whatever 130

of the glass plate from its properly leveled position.

Having described the preferred form of my invention, I claim:

- 5 1. In combination with a silvering table, a vertical plate supporting plunger, yielding means for moving said plunger upwardly, means for moving said plunger downwardly, and means for frictionally engaging the plunger to hold it in any set position as regards its vertical movement.
- 10 2. In combination with a silvering table, a vertical plate supporting plunger, yielding means for moving said plunger upwardly, means for moving said plunger downwardly, and means for frictionally gripping the plunger to hold it in any set position as regards its vertical movement.
- 15 3. In combination with a silvering table, a vertical plate supporting plunger, yielding means for moving said plunger upwardly, means for moving said plunger downwardly, and means coöperating with the last mentioned means for frictionally
- 20 25 engaging the plunger to hold it in any set position as regards its vertical movement.
- 25 4. In combination with a silvering table, a vertical plate supporting plunger, yielding means for moving said plunger downwardly, and means for holding the plunger in any set position as regards its vertical movement, said means embodying a clamp encircling the plunger, and means coöperating with the means for moving the plunger downwardly to compress the clamp about the plunger.
- 30 35 5. In combination with a silvering table, a vertical plate supporting plunger, means including a weight for normally moving the plunger upwardly, means including a horizontally movable wedge for lifting the weight and for moving the plunger downwardly, and means coöperating with the horizontally movable wedge for frictionally
- 40 45 engaging the plunger at any set position to hold it against vertical movement.
- 45 6. In combination with a silvering table, a vertical plate supporting plunger, means including a weight for normally moving the plunger upwardly, means including a horizontally movable wedge for lifting the weight and for moving the plunger downwardly, and means coöperating with the horizontally movable wedge for frictionally
- 50 55 engaging the plunger at any set position to

hold it against vertical movement, said means including a clamp surrounding the plunger and a clamp lever connected to the clamp and to the horizontally movable wedge.

7. In combination with a silvering table, a vertical plate supporting plunger, means including a weight for normally moving the plunger upwardly, means including a horizontally movable wedge for lifting the weight and for moving the plunger downwardly, and means coöperating with the horizontally movable wedge for frictionally engaging the plunger at any set position to hold it against vertical movement, said means including a clamp surrounding the plunger and a clamp lever connected to the clamp and resiliently connected to the horizontally movable wedge so that when the wedge is moved from under the weight the lever will be thrown to compress the clamp about the plunger.

8. In combination with a silvering table, a vertically movable plate supporting member, a yielding means for raising said member, means for lowering said member, and means coöperating with the lowering means to frictionally engage said member and hold it vertically unmovable.

9. In combination with a silvering table, a vertically movable plate supporting member, a weight connected with said member and adapted by its downward movement to raise said member, means to raise said weight and to thereby lower said member, and means for frictionally engaging said member to hold it against vertical movement, said means coöperating with said weight raising means to operatively engage and hold said member when said means is moved out of operative relation to said weight.

10. In combination with a silvering table, a vertically movable plate supporting plunger, a weight means for moving said plunger upwardly to raise the plate supported thereon, means for moving the plunger downwardly, and frictional means for engaging the plunger to hold it vertically immovable.

In witness that I claim the foregoing I have hereunto subscribed my name this 7th day of April 1916.

GEORGE GLAUDEL.
